CLAIM

The ornamental design for a vehicle servicing step, as shown and described.

DESCRIPTION

FIG. 1 is a perspective view of my new design for a vehicle servicing step shown at a reduced scale mounted on the tire of a vehicle. The broken lines showing the vehicle are for illustrative purposes only and form no part of the claimed design.

FIG. 2 is an exploded plan view thereof;

FIG. 3 is an exploded side elevational view of the first side thereof, the opposing side view being the mirror image thereof;

FIG. 4 is a bottom view thereof;

FIG. 5 is a front view thereof;

FIG. 6 is an enlarged fragmentary rear left side perspective thereof; and,

FIG. 7 is a rear view thereof.
